UNITED STATES PATENT OFFICE.

WILLIAM JOHNSON, OF LAMBERTVILLE, NEW JERSEY.

VALVE-GEAR FOR STEAM-ENGINES.

SPECIFICATION forming part of Letters Patent No. 241,495, dated May 17, 1881.

Application filed March 18, 1881. (Model.)

To all whom it may concern:

Be it known that I, WILLIAM JOHNSON, a citizen of the United States, residing at Lambertville, in the county of Hunterdon and State 5 of New Jersey, have invented certain new and useful Improvements in Valve-Gear for Steam-Engines; and I do hereby declare the following to be a full, clear, and exact description of the invention, such as will enable others skilled 10 in the art to which it appertains to make and use the same, reference being had to the accompanying drawings, and to the letters or figures of reference marked thereon, which form a part of this specification.

15 My invention consists in a governor mechanism for controlling the cut-off valves of engines, whereby the point of cut off is automatically determined by the speed of the engine, the construction being more fully hereinafter 20 described.

In the accompanying drawings, Figures 1, 2, and 5 represent end elevations of my improved cut-off governor, Figs. 2 and 5 showing modifications. Fig. 3 is a sectional view taken on 25 line $x-x$ of Fig. 2 of the drawings. Figs. 4 and 6 represent a fixed and an adjustable eccentric as applied to Fig. 3. Fig. 7 is a modified view of the adjustable eccentric shown in Fig. 4.

30 Similar letters refer to similar parts throughout the several views.

A is the engine-shaft.

B is a disk (or it may be the fly-wheel of the engine) securely attached to shaft A.

35 C is a swinging arm or pendulous lever, one end of which is attached to disk B by pivot e , while the other end has a cylindrical flange, a , surrounding shaft A.

D is an eccentric ring, fitted to turn freely 40 upon the cylindrical flange of C.

E E are reactionary levers, supported upon stud-pins $e' e'$ fixed in disk B, one end of each of said levers being connected to the pendulous lever C upon one side of their center of motion, while the opposite ends are connected to the eccentric ring D upon the other side by means of the connecting-rods $b b'$.

F F are weights connected to the reactionary levers by lever-arms H H.

50 G G are springs attached to disk B and levers E E.

The operation is as follows: Motion is communicated to the engine-shaft by the action of the steam against the piston in the usual manner. The centrifugal force of the weights and tension of the springs are adjusted to an equilibrium for the desired speed. Any change of speed will cause a movement of the weighted arms, the direction of which will depend upon whether the change is an increase or a decrease 60 of the speed of the engine, and whether the weights or the springs by reason thereof have a preponderating force. The movement of the weighted arms will cause a corresponding movement of the reactionary levers, and by 65 means of the connecting-rods therefrom a simultaneous movement will be given to the pendulous lever and eccentric ring, which form a compound eccentric, the pendulous lever being moved across while the eccentric ring is 70 turned around the axis of the shaft, and as the cut-off valve is connected to the eccentric by the usual arrangement of straps and rods, it will be seen that the automatic movement 75 of the weighted arms will control the movement of the cut-off valve, and that the point of cut off will thus be automatically determined by the speed of the engine.

In the modification shown in Fig. 2 the connecting bar or casting K is moved across the 80 axis of the shaft by the weighted lever-arms. The eccentric ring D turns freely upon the cylindrical flange a of K, and has a pin, d' , which projects from one side into a slot in the fixed eccentric L, as shown in Fig. 4. The movement of the connecting bar or casting will cause the eccentric ring to turn thereon by reason of the pin and slot, and the combined movement will change the throw and lead of the eccentric, by which the speed of the engine is automatically controlled and governed, as before described. In that of Fig. 5 the pendulous lever is moved across the axis of the shaft by the weighted lever-arms, and the eccentric ring is 90 a part of or is firmly fixed upon the cylindrical portion of the pendulous lever, and moves with but not upon the pendulous lever. The movement of the pendulous lever across the axis of the shaft determines the position of the eccentric, stroke of valve, and consequent 95 point of cut off, as will be clearly understood from the drawings and foregoing description.

- I am aware that an eccentric has been revolved or turned within an eccentric ring by means of weights and springs for the automatic adjustment of engine-valves, the said eccentric ring being held from turning with the eccentric by means of a pin in the eccentric ring, which slides in a slot in the fixed eccentric or disk, and by which the eccentric ring is driven or made to revolve with the shaft. I
 10 am also aware that a pendulous lever having a fixed eccentric has been moved across the axis of the driving-shaft by means of weighted levers and springs revolving therewith, said movement of the pendulous lever being effected
 15 by turning a collar or sleeve upon the shaft; but with neither of these arrangements does the construction here shown conflict. I therefore do not claim the same; but
 20 What I do claim as my invention, and wish to secure by Letters Patent, is—
 25 1. A cut-off mechanism consisting of a flanged plate and an eccentric ring, both adjusted across and around the axis of the shaft by means of a governor, as and for the purpose set forth.
 2. In a governor cut-off, an adjustable compound eccentric adapted to be moved across and around the axis of its driving-shaft by means substantially as described, whereby as
 30 the work increases or decreases the speed of the engine is automatically controlled.
 3. In a cut-off mechanism, weighted levers revolving with the driving-shaft, in combination with a compound eccentric consisting of

a concentric ring and an eccentric ring, which 35 are moved across and around the axis of the driving-shaft by means substantially as described, and for the purpose set forth.

4. In a governor cut-off a pendulous lever one end of which is adapted to be moved across 40 the axis of the driving-shaft by weighted levers attached to a disk revolving in unison with the pendulous lever, combined with an eccentric ring, the eccentricity of said ring, combined with the eccentricity caused by the 45 pendulous lever moving across the shaft, serving to control and regulate the movements of the engine.

5. In a governor cut-off, a pendulous lever one end of which is adapted to be moved across 50 the axis of the driving-shaft by weighted and pivoted levers, combined with an eccentric ring which moves with and around a flange placed upon the pendulous lever, and is also connected with the above pivoted levers, as 55 and for the purpose set forth.

6. In a governor cut-off, the revolving disk or wheel provided with the reactionary bell-crank lever or levers, and adapted by connecting-rods to convey a double movement to the 60 compound eccentric, as and for the purpose set forth.

In testimony whereof I have affixed my signature in presence of two witnesses.

WM. JOHNSON.
